DESIGN FOR A TABLE JOINTER

**Theron L. Hedgpeth, Oak Park, Ill., assignor to
Duro Metal Products Company, Chicago, Ill., a
corporation of Illinois**

Application April 1, 1935, Serial No. 56,144

Term of patent 14 years

To all whom it may concern:

Be it known that I, Theron L. Hedgpeth, a citizen of the United States, residing at Oak Park, in the county of Cook and State of Illinois, have invented a new, original, and ornamental Design for Table Jointers, of which the following is a specification, reference being had to the accompanying drawing, forming part thereof.

The figure is a view in perspective of a table jointer embodying my design.

The rear of the device is substantially plain and, aside from features of utility, has substantially the same appearance as the front portion shown.

I claim:

The ornamental design for a table jointer as shown and described.

In witness whereof, I hereunto subscribe my name, this 28th day of March, 1935.

HERON L. HEDGPETH.
